(57) **CLAIM**

The ornamental design for a ceiling light, as shown and described.

DESCRIPTION

FIG. 1 is a rear, left and top perspective view of a ceiling light, showing my design.

FIG. 2 is a front, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the ceiling light that form no part of the claimed design.
